UNITED STATES PATENT OFFICE.

FRANK A. HOWSON, OF BROOKLYN, NEW YORK.

VENETIAN BLIND.

SPECIFICATION forming part of Letters Patent No. 366,837, dated July 19, 1887.

Application filed April 5, 1887. Serial No. 233,729. (No model.)

To all whom it may concern:

Be it known that I, FRANK A. HOWSON, a subject of the Queen of Great Britain, residing at Brooklyn, in the county of Kings and State 5 of New York, have invented a new and Improved Venetian Blind, of which the following is a full, clear, and exact description.

This invention relates to the construction of blinds of that class commonly called "Venetian" blinds, the object of the invention being to provide a blind which may be rolled together at either the top or the bottom of the window, or which may be slid upward or downward into a properly-formed recess, the invention 15 consisting in the construction and arrangement of parts, as will be hereinafter fully described and claimed.

Reference is to be had to the accompanying drawings, forming a part of this specification, 20 in which similar figures of reference indicate corresponding parts in all the views.

Figure 1 is a perspective view of a portion of a blind constructed in accordance with the terms of my invention. Fig. 2 is a cross-sectional view taken upon a line corresponding approximately with the line xx of Fig. 1, and Fig. 3 is a cross-sectional view taken upon a line corresponding with the line yy of Fig. 1. Fig. 4 is a side view, on a reduced scale, of 30 the blind partially wound upon a roller.

The slats 10, entering into the construction of the blinds illustrated in the drawings above referred to, are formed with curved upper edges, 2, and with correspondingly-shaped recesses 3 in their lower edges, and near each end of the slats I form apertures that are adapted to receive metallic bands 11; or, if preferred, wires could be substituted for the bands. One wall of each lower recess, 3, is 40 cut away or chamfered, as shown at 4, the chamfer extending inward to a point adjacent to the vertical wire or band receiving apertures, so that the strung slats forming the blind may be rolled upon a roller after the 45 manner of an ordinary shade, which would be impossible if the recess were not chamfered, as

described. Heretofore the lower edges of the slats have been formed with **V** or **U** shaped recesses, which would prevent the blind from being rolled, though it could be curved somewhat to enter curved ways above the window; but such a construction I do not claim. 50

The central portion of each slat is cut away, the lower defining wall of the cut so formed extending upward at an angle from the front 55 or outer face of the slat, so that when two slats are strung together upon their supporting bands or wires 11 the lower edge of the outer face of each slat will be in a plane beneath the upper defining edge of the recess 60 formed in the slat-body.

Instead of having a single recess in each slat, two or more recesses might be formed therein, and in this case the uncut portions of the slats between the recesses would be apertured to 65 receive the stringing bands or wires. In forming these recesses they might be arranged so as to impart the effect of a paneled blind.

By forming the slats as described I provide for the rolling or sliding of the blinds into 70 properly-arranged housings located at either the top or the bottom of the window in connection with which the blinds are arranged.

Having thus fully described my invention, I claim as new and desire to secure by Letters 75 Patent—

A Venetian blind formed of the slats 10, cut away on their central upper portions, curved on their upper edges at 2, recessed on their lower edges, as at 3, to receive the curved 80 edges 2 of the slat below, and one wall of each recess 3 being cut away or chamfered, as at 4, to allow the blind to be rolled upon a roller after the manner of an ordinary shade, the vertical apertures, and the flexible wires or 85 bands 11, passing through the apertures, substantially as set forth.

FRANK A. HOWSON.
